Primary Examiner—Brian N. Vinson**[57] CLAIM**

The ornamental design for a pacifier holder, as shown and described.

DESCRIPTION

FIG. 1 is a front and left side perspective view of a pacifier holder showing my new design;

FIG. 2 is a reduced top, front, and right side perspective view thereof;

FIG. 3 is a front and left side perspective view thereof;

FIG. 4 is a top plan view thereof;

FIG. 5 is a left side elevational view thereof; and,

FIG. 6 is a front elevational view thereof.

The broken-line disclosure in the views is for illustrative purposes only and forms no part of the claimed design.
